UNITED STATES PATENT OFFICE.

CONRAD A. DIERIG, OF LAWRENCE, MASSACHUSETTS.

NECKTIE-HOLDER.

1,191,576.

Specification of Letters Patent. Patented July 18, 1916.

Application filed April 4, 1916. Serial No. 88,846.

To all whom it may concern:

Be it known that I, CONRAD A. DIERIG, a citizen of the United States, residing at Lawrence, in the county of Essex and State 5 of Massachusetts, have invented certain new and useful Improvements in Necktie-Holders; and I do hereby declare the following to be a full, clear, and exact description of the invention, such as will enable others 10 skilled in the art to which it appertains to make and use the same.

This invention has for its object to provide an efficient and invisible holder attachable to a collar button for supporting or holding the 15 knot of the necktie against shifting and to give the knot a full and attractive appearance.

Another object is the provision of a necktie holder embodying such novel features of 20 construction that the holder may be secured in various adjusted positions with relation to the collar button.

With these and other objects in view, the invention consists in the novel construction, 25 combination and arrangement of parts as will be hereinafter specifically described, claimed and illustrated in the accompanying drawing, in which:

Figure 1 represents a front view of a collar, partly broken away, and necktie, illustrating the tie holder applied thereto, Fig. 2 represents a perspective view of the holder removed and in normal expanded condition, Fig. 3 represents a perspective view of the tie holder removed, illustrating the tie-receiving ring in compressed condition, and Fig. 4 represents a perspective side view of a modified type of the holder.

Referring to the drawing in detail, where- 40 in similar reference numerals designate cor- responding parts throughout the several views, the numeral 5 indicates a substan- tially circular split ring constructed of spring metal and having the free ends 6 over- 45 lapped.

The free ends of the legs 7 of a substan-

tially U-shaped clip 8 are permanently connected with the overlapped ends 6 of the spring ring and are connected at their opposite ends by the curved web portion 9. The 50 clip 8 is preferably constructed of spring wire and the inherent tension thereof normally retains the free ends of the legs 7, which are connected with the ends of the ring 5, in relatively close relation. The portions of the legs 7 disposed between the web 55 9 and the spring 5 are bent to provide a plurality of pairs of opposed collar button engaging members 10, which, when the clip is in normal position, as illustrated in Fig. 2, 60 provides a plurality of eyes of less internal diameter than the diameter of the head of the collar button 11, Fig. 1, so as to insure against accidental disengagement of the tie 65 holder therefrom.

In use, the necktie 12 is applied to the collar 13 and tied in the usual manner and the free ends thereof are slipped through the ring 5 and the latter is moved upwardly under the outermost loop of the necktie knot 14, 70 as illustrated in dotted lines in Fig. 1. By applying pressure to the opposite sides of the ring 5 the legs 7 are spread apart, as clearly illustrated in Fig. 3, and in this position the head 11 is gripped between the legs 75 and when the ring is released the tension thereof moves the legs 7 together, thereby causing one pair of spring members 10 to firmly grip the shank of the collar button 11 and thus secure the holder in position there- 80 on. It will be understood that by engaging the collar button shank with any one of the several curved members 10 the ring 5 may be adjusted at any desired position with relation to the collar button.

In the modification of the invention illus- 85 trated in Fig. 4, the numeral 15 indicates a split spring ring having the free ends of a substantially U-shaped clip 16 connected with the ends thereof and secured centrally 90 to a shank 17, having an angular lower end 18, which, when the holder is applied to the

necktie, projects below the loop 14 of the tie knot and exposes a jewel or other ornament 19 attached to the free end thereof.

What I claim is:

- 5 1. A tie holder including a split necktie-receiving ring having the free ends overlapped, and means carried by the overlapped ends of said ring for securing the latter in position upon a collar button.
- 10 2. A tie holder comprising a split tie-re-

ceiving ring having the free ends overlapped, and a substantially U-shaped collar button-engaging clip carried by the free ends of said ring.

In testimony whereof I affix my signature 15 in presence of two witnesses.

CONRAD A. DIERIG.
